(Cl. D62—4)

To all whom it may concern:

Be it known that I, George B. Herbster, a citizen of the United States, residing at Cleveland, in the county of Cuyahoga and State of Ohio, have invented a new, original, and ornamental Design for a Combined Air Circulator and Diffuser, of which the following is a specification, reference being had to the accompanying drawing, forming a part thereof.

Figure 1 is a perspective view exposing the bottom and side of the combined air circulator and diffuser embodying my design, and

Figure 2 is a side elevation thereof.

I claim:

The ornamental design for a combined air circulator and diffuser, substantially as shown.

GEORGE B. HERBSTER.
